COCKTAIL TABLE

Joseph E. Adkinson, York, Pa., assignor to Weiman Co.,
Inc., Rockford, Ill., a corporation of New York

Filed Sept. 17, 1962, Ser. No. 71,709

Term of patent 14 years

(Cl. D33—14)

Fig. 1.

Fig. 2.

FIG. 1 is a perspective view of a cocktail table showing my new design, and

FIG. 2 is a side view, the opposite side being the same.
I claim:

The ornamental design for a cocktail table, substantially as shown.
